AUTOMATIC CONTROL PLUG FOR
ELECTRICAL APPLIANCES

David B. Scoville, Crystal Lake, Ill.

Application August 18, 1933, Serial No. 685,674

5 Claims. (Cl. 200—38)

This invention relates to improvements in automatic control plugs for electrical appliances, and more particularly for electric toasters, grills and like utensils for the cooking or preparation of food products wherein the application of heat requires more or less accurate control.

The object of the invention is to provide a plug of substantially the same size and design as the standard plug used for connecting the cord or conductor cable directly with the appliance and incorporating therein a compact time switch mechanism which can be set to operate automatically to shut off the current after the lapse of a given period of time.

15 A further object of the invention is to provide for the varying of the period of time during which the current is supplied to the heating element of the appliance in order to regulate the application of heat to the degree of toasting or cooking required.

20 A further object of the invention is to provide a device which may be substituted for the standard plug of a non-automatic electrical appliance and thus convert it into an automatic device at very little cost. Perhaps the best example of its utility is in the field of electric toasters which are now being made to operate automatically, but at a cost considerably more than the ordinary or non-automatic styles and so much so that they are, at present at least, beyond the means of the average purchaser. Moreover, the vast majority of the toasters in use are of the non-automatic type, so that the ability to equip relatively inexpensive toasters either old or new, to operate automatically by merely substituting one plug for another at but a trifling additional cost is a real boon to the users as well as to the manufacturers of the older style devices.

25 Thus, while the idea of an automatic toaster is already a reality, the merit of the present invention resides in the simplicity and compactness of the control mechanism which permits it to be incorporated in a plug which can be interchanged with the ordinary type of plug, without otherwise altering the toaster or its electrical connections.

30 A preferred embodiment of the invention is disclosed in the accompanying drawing, in which Figure 1 is a view of the plug in elevation;

35 Figure 2 is a view in longitudinal section taken on line 2—2 of Figure 1;

40 Figure 3 is a view in elevation of the inside of the top section of the plug when the same is parted along the line 3—3 of Figure 2;

45 Figure 4 is a view in elevation of the inside of the bottom section of the plug when parted

along the same line as in Figure 3 but in the direction of the arrows 4—4;

5 Figure 5 is an enlarged detail view in cross section through the plug as taken on line 5—5 of Figure 2; and

Figure 6 is a detail view of the escapement mechanism of the clock movement as taken on line 6—6 of Figure 2.

10 It will be observed at the outset that, so far as the electrical connections are concerned, the automatic plug follows closely the construction and design of the ordinary plug, in fact, the only departure is a slight increase in the length to accommodate the added switch control mechanism. As well known in the art, a more or less standard type of plug and plug connection has been developed for electrical household appliances, namely, a casing of insulating material having a pair of connectors exposed at one end to fit a pair of post-like terminals on the appliance, the plug itself being attached to one end of a cord having the usual connector at the other end for inserting into a light socket or outlet.

15 Following the standard design, the plug consists of a flat elongated casing 1 of a suitable insulating material such as bakelite which is moulded in two sections 1^a and 1^b parted on a plane bisecting the casing in the direction of its width. Bosses 2, 2 are moulded on the interior of each half or section near opposite ends, and screws 3, 3 are inserted through registering holes drilled and tapped in these bosses. When assembled the two halves of the casing 1 provide a chamber in which are mounted the electrical conductors and the time switch mechanism.

20 The electrical conductors in the plug have the form of flat metal strips 4 and 5 and are anchored in the upper section 1^a (Figure 3) by means of rivets 6, 6 passing through enlarged portions at their ends. One of the strips 4 is continuous and lies along the side of the casing, whereas the other strip 5 is divided into two parts to form a simple form of switch for making and breaking the circuit, as will presently be described in greater detail.

25 At the inlet end of the plug the ends of the conductor strips 4 and 5 are provided with the usual binding posts 7, 7 to which the ends of the wires forming the cord 8 are attached, said cord entering through an opening 9 in the end of the plug. At the outlet end of the plug are the endwise opening sockets 10, 10 before mentioned, and separated by the longitudinally elongated boss 3. Within these sockets are the

connector clips 11, 11 electrically connected at their inner ends to the conductor strips by the same rivets 6, 6 which anchor both to the casing section 1^a.

- 5 Located centrally of the interior of the plug and between the two conductor strips 4 and 5 is the time controlled switch mechanism, the parts thereof being rotative about two parallel axes spaced apart along the longitudinal center line of the plug and extending transversely of the depth of the casing. This mechanism is essentially a variation of the so-called clock movement including a winding spring operatively connected with a train of gears controlled by a 10 simple form of escapement, and a driven cam member which acts directly upon the switch to make and break the circuit through the plug.

- For convenience in assembly a part of the control mechanism, consisting of the gear train and escapement of the clock movement, is mounted 15 in one section (the lower section 1^b) of the plug casing, while the remainder, including a winding spring and knob together with the cam are mounted on the other (upper) half of the casing carrying also the conductor strips 4 and 5. The parts of the control mechanism are thus separated into groups which are assembled independently of each other on their respective casing sections, the connections between them being 20 made by means of spring fingers on the cam which register with projections on the face of the adjacent wheel of the clock movement when the two halves of the plug are assembled.

- Referring first to the parts carried by the upper half of the plug casing, the winding spring 13 is a simple form of clock spring coiled about a cylindric boss 14 on the inner face of the casing section and having an axial bore in which is a shaft 15 (Figure 5). On the inner end of 25 the shaft is fixed the cam 16 consisting of a disc having a deep marginal flange surrounding and enclosing the winding spring, the outer end of the latter being fixed to a cam by means of a rivet 17 which projects from the outer face of 30 the flange to provide a stop member for a purpose to be later set forth. The inner end of the spring is anchored to the boss 14 as by bending the end of the spring at right angles, as at 13^a, and inserting it into a slot 14^a in the surface of 35 the boss (Figure 5). Fixed to the outer end of the shaft 15 and exterior of the plug casing is the spring winding knob 18, preferably of frusto-conical shape having its tapered face knurled and direction and position arrow marked on its 40 circular end face as shown in Figure 1.

- Formed in the face of the cam flange is a notch 16^a having a radial stop shoulder on one side and a gradually inclined surface leading from the periphery of the cam to the base of the notch. Now lying adjacent the cam and in a general tangential relation thereto is the longer portion 5^a of the conductor strip 5, bent to curve 45 inwardly toward the cam and thence beyond where it terminates in overlapping and normally spaced relation to the shorter portion 5^b of the same conductor strip. These overlapping portions thus form the make and break contact of the circuit, and if desired may be provided with suitable contact points. On the longer flexible contact strip 5^a is a finger 19 projecting toward the cam and adapted in normal position to engage the cam notch 16^a, in which position the contact points are separated and the circuit open. And finally, on the outer face of the 50 cam are fixed a pair of spring ratchet fingers 75

20, 20 curved to conform to the arc of a circle and riveted at their corresponding ends at points diametrically opposite each other and midway between the center and periphery of the cam face. These ratchet fingers extend in the same direction, that is, clockwise from their fixed ends and through an arc of 90°, and are bent outwardly from the face of the cam so that their free ends are spaced a short distance therefrom. As heretofore explained, these ratchet fingers provide the connection between the parts of the control mechanism carried by the upper half section of the casing just described, and those parts of the mechanism carried by the lower section now to be described and identified. Briefly, 10 the parts on the lower section constitute a simple clock movement made up of two series of alternately intermeshing gears and pinions, one series being journaled on a stub shaft 21 anchored at one end in the wall of the casing section and in axial alignment with the winding spring 13, and the other series on a similar stub shaft 22 spaced a short distance from it. 15

Since clock movements are well known, it will not be necessary to identify each individual gear and pinion, except to point out that it is made up of several units, each consisting of an integral gear wheel and pinion, which progressively mesh with each other throughout the complete train, the gear of first unit of one series meshing with the pinion of the next unit, and so on. 20 In this manner the desired gear reduction is obtained between the first and last units in the train. And finally, the rotation of the units is regulated by the action of an escapement upon 25 one of the gear wheels, functioning in the usual way to effect the slow intermittent motion peculiar to clock movements.

In the particular train disclosed, the first member of the train is a large gear wheel 23 on the 30 end of the shaft 21 and immediately opposite the cam 16, and having a series of annularly arranged projections and ratchet teeth 23^a stamped therein and registering with the spring fingers 20, 20 on the cam. This gear wheel 23 35 meshes with the pinion of a unit 24 on the shaft 22, which in turn drives a similar unit 25 on the shaft 21, this last unit driving still another unit 26 on the shaft 22. Now, the gear wheel of this last unit acts as the escapement wheel, 40 having pointed teeth as shown in Figure 6. On the shaft 21 opposite the escapement wheel is a disc 27, somewhat thicker and heavier than the gear wheels and having a boss 27^a to which is fixed the escapement lever 28 consisting of a metal strip bent in U-shape with inwardly curved fingers 45 engaging the teeth of the escapement wheel. The disc or balance wheel 27 rocks or oscillates on the shaft 21 with the escapement movement and by reason of its weight and inertia controls 50 the timing of the movement.

As hereinbefore pointed out, the gear train or clock movement just described is a self-contained unit wound by the lower section of the plug casing, and in assembling the two sections 55 the projections or ratchet teeth 23^a on the gear wheel 23 register with the spring fingers 20 on the cam 16 and establish a pawl and ratchet connection between the two groups or parts of the switch control mechanism.

The manipulation of the switch control mechanism is quite simple, consisting merely in turning the knob in a clockwise direction through something less than one complete turn for the maximum heating period; about one-half turn 70 75

for the minimum period and to an intermediate position for one corresponding intermediate period of heating. These stages of heat duration are gauged to the degree of toasting that 5 may be desired, as for example, well done or "dark", slightly done or "light" and medium done. Suitable position indicators are marked on the casing around the edge of the knob together with spaced markers corresponding in 10 number to the projections or ratchet teeth 23^a over which the spring pawl fingers 20 click when turning the knob in the clockwise direction to wind the spring.

Thus assuming that the toaster is connected 15 with the knob in the "off" position and the bread to be toasted is in place, the operator merely turns the knob in a clockwise direction to the position for the desired degree of toasting and then releases it. Now in turning the knob, 20 the cam 16 rotates with it but its rotation is not transmitted to the gear train because the ratchet fingers 20 on the cam merely click over the teeth 23^a on the first wheel 23 of the clock movement. However, with the initial turning of 25 the cam, the circuit is closed by the cam action of the finger 19 on the switch member 5^a sliding out of the cam notch 16^a and into the flange of the cam. Moreover, the spring 13 is wound by the rotation of the cam, so that on releasing 30 the knob the cam is turned in the opposite direction under the action of the spring unwinding, but its return movement is regulated by the clock movement which now functions through the pawl and ratchet connection. This 35 return movement of the knob and cam is relatively slow, taking, say, one or more minutes, depending upon the length of time required for toasting, and when the return movement is complete the cam comes to a stop at its starting point simultaneously opening the circuit as the finger 19 on the switch member 5^a again enters the cam slot.

This procedure is repeated for each toasting 40 operation, in each case the duration of the toasting being controlled by the position to which the winding knob is turned from the "off" position before releasing it. And in this connection it will be noted that the mechanism is so designed that one revolution of the knob is the maximum 45 of the winding movement. Therefore, to prevent an inexperienced person from turning the knob in excess of this limit, the stop member 17 is provided on the cam. Thus when the knob has been turned through one revolution, the stop 50 17 will strike the finger 19 and prevent its further turning.

Since different makes of toasters vary somewhat in the intensity of heat and therefore the 55 period required for toasting, the time adjustments of the plug can also be utilized in adapting it to the particular toaster to which it is applied, so that once the required period of time for proper toasting is determined by experiment, uniform toasting can be obtained thereafter by turning the knob to the same point. In fact, it would be an obvious expedient to provide means for limiting the turning of the knob to any desired amount, and when once set there would be no need thereafter for visually determining the point at which the knob is to be released. In other words, it is equally if not 60 more important that the plug be adjustable to different makes of appliances, as it is that it can be regulated for different degrees of toast-

ing, since uniform performance is the essential requirement.

In conclusion, therefore, the merit of the invention resides in its construction as well as its application in the art. Thus, aside from the 5 fact that makes possible the automatic operation of electric toasters and like appliances at but little additional cost and without altering its construction or design, the mounting of a simple yet practical time controlled switch mechanism within a plug of substantially standard dimensions is a novel accomplishment, particularly in the grouping of the parts into separate units mounted in the sections of a two-part casing, a construction that affords ease of manufacture and assembly, not to mention the simplicity of repairs and replacement of parts.

Having set forth a preferred embodiment of my invention, I claim:

1. In a connector plug for electrical appliances 20 comprising a casing divided longitudinally into sections, the combination of a contact switch, a switch operating cam and a winding spring mounted in one section and a clock movement mounted in the other section and including a disc 25 adapted in the assembly of said casing to be positioned face to face with said cam, and pawl and ratchet members carried by said cam and disc and providing a detachable connection between said cam and clock movement. 30

2. In a connector plug for electrical appliances comprising a casing divided into sections and having a switch mounted therein, the combination of a rotative cam mounted on one of said sections and having operative connection with said switch 35 whereby the latter is shifted into circuit closing position in the rotation of said cam from a normally "off" position, a coil spring mounted in said section adjacent said cam and connected therewith for winding in the rotation of said cam, and 40 a clock movement mounted in the other section and including a disc rotative on an axis coincident with the axis of said cam, the latter having resilient fingers adapted to engage teeth on the face of said disc to interconnect the same when 45 the sections of said casing are assembled.

3. In a connector plug for electrical appliances comprising a casing divided longitudinally into two half sections, the combination of a switch, a manually rotative switch operating cam, and a 50 winding spring mounted in one of said sections, and a clock movement mounted in the other section and including a gear wheel rotative on an axis coincident with the axis of said cam, the latter having resilient fingers adapted to engage 55 teeth on the face of said gear wheel to interconnect the same when the sections of said casing are assembled.

4. In a plug connector for electrical appliances comprising an insulated casing parted longitudinally into two sections and enclosing a switch including a flexible metal strip adapted to be flexed into and out of circuit closing position, the combination of a rotative cam having a notch in its periphery to receive a projection on said contact strip in the "off" position of said switch, a manually rotative finger piece exterior said casing for rotating said cam disc, and a coil spring connected with said cam, all mounted as a unit in one of said sections, and a clock movement 60 forming another unit mounted in the other section of the casing and including a disc in axial alignment with said cam, said cam and disc co-acting spring fingers and ratchet teeth on their 65 opposing faces for effecting a detachable connection. 75

tion between the units mounted in their respective sections in the assembly of the casing.

5. In a plug connector for electrical appliances comprising an insulated casing parted longitudinally into two sections, the combination of a switch including a metal contact strip adapted to be flexed into and out of circuit closing position, a cam adapted for bearing contact at its periphery with said strip and having a notch therein normally positioned to receive a projection on said strip in the "off" position of said switch, a manually operative finger piece exterior said casing for rotating said cam disc, and a coil spring adapted to be wound in the rotation of said finger

piece, all of said parts forming a unit mounted in one of said casing sections, and a clock movement journaled on stub shafts supported by the other section of the casing and including a gear wheel spaced from and in axial alignment with said cam and having annularly arranged projections in the face thereof, and spring fingers mounted on the face of said cam and adapted to engage the projections on said gear wheel to connect the clock movement in one section with the parts in the other section when the same are assembled.

DAVID B. SCOVILLE.
